MEANS FOR CHECKING PICKER STICKS

Walter J. Budzyna, East Douglas, Mass., assignor
to Draper Corporation, Hopedale, Mass., a cor-
poration of Maine

Application February 19, 1944, Serial No. 423,039

6 Claims. (Cl. 139—165)

The present invention relates to picking mechanisms for fly shuttle looms and, as illustrated herein, relates more particularly to picker stick checking mechanisms.

One prior type of picker stick checking mechanism comprises a depending support attached to the lay beam and causing a flexible check strap loop within which the picker stick oscillates and which is engaged and moved by the picker stick at each end of its oscillation. In devices of this type it is necessary to provide friction means for retarding the movement of the strap and also to provide readily accessible adjusting means for said friction means. In such prior devices, it has not been possible conveniently and accurately to adjust the friction means and hence proper checking of the picker stick has not always been effected.

One object of the present invention, accordingly, is to provide a picker stick checking mechanism wherein the friction means may be conveniently and accurately adjusted. To this end, the present invention contemplates a bracket secured to the front surface of the lay and having thereon an angularly adjustable member carrying a pair of friction fingers which engage opposite faces of a check strap and which by reason of their angular adjustment, retard the check strap as it is moved by the picker stick.

With the above and other objects and features in view, the invention will now be described with particular reference to the accompanying drawing which illustrates a preferred embodiment of the invention and in which:

Fig. 1 is a view in front elevation of a portion of the left hand end of a lay embodying the present invention;

Fig. 2 is a plan view of the mechanism shown in Fig. 1;

Fig. 3 is a perspective view of the friction fingers; and

Fig. 4 is a view, partly in section, taken along line IV—IV of Fig. 1.

The drawing shows but a part of a loom having the invention applied thereto. The parts which are not shown may be of any usual construction and form no part of the present invention.

The drawing shows a portion of the left hand end of a usual lay beam 10. The lay beam at its end is provided with the usual shuttle box (not shown) into and out of which the shuttle is picked by a picker stick 12. The picker stick 12 oscillates in the slot 14 in the usual manner.

The lay is provided with a check strap 16, the

ends thereof being clamped and supported in a bracket 18 of usual construction fixed to and supported by the lay beam 10 by bolts 20.

A second bracket 22 is secured to the other side of the lay opposite to the bracket 18 and provides means for supporting and checking the movement of the strap. The bracket 22 has a portion 24 which extends below and fits against the bottom of the lay 10 and also has a flange 26 which extends upwardly against the front side of the lay. The bracket 22 is secured to the lay by bolts 28 which extend through slots 30 formed in the portion 24. The flange 26 is provided with a forwardly extending shelf or support 32 which supports a frame 34 having friction fingers 36 and 38 thereon.

The frame 34 is angularly adjustable on the bracket 22 in order to vary the path of movement of the check strap 16. The frame 34 includes an upper horizontal portion 40 connected to, or formed as a part of, the friction finger 38. A hole is provided in the free end portion of the portion 40 for receiving a bolt 42 which passes upwardly and through a hole formed in the forwardly extending shelf 32. The bolt acts as a pivot about which the frame 34 is rotated to adjust the position of the fingers 36, 38 relatively to the bracket 22 and as a means for locking the friction finger frame in adjusted position.

The lower ends of the fingers 36, 38 are connected by a horizontal frame member 44. The portion 40 of the friction finger frame 34 is provided with a forwardly projecting tongue 46 which may conveniently be gripped by a pair of pliers or a wrench to move the frame into adjusted position and to hold the same in said position while the clamping nut 48 is being tightened.

The portion 40 is located angularly with respect to the portion 44 so that when the friction finger frame is rotated the position of the fingers 36, 38 will be varied relatively to the path of movement of the check strap 16 when it is moved by the picker stick. For example, if the frame is rotated in a clockwise direction from the position shown in Fig. 2, the finger 36 will move forwardly and the finger 38 will move rearwardly. Thus when the frame is so adjusted, the check strap 16 will be caused to follow a more sinuous path and hence the retarding action of the fingers 36, 38 is increased. If on the other hand, it is desired to decrease the retarding effect of the friction fingers, the frame can be rotated in the opposite direction and thus provide a less sinuous path for the check strap to follow.

Having thus described a preferred embodiment

of the invention, what I claim as new and desire to secure by Letters Patent of the United States is:

1. A friction device for a picker stick check mechanism of the type wherein a flexible looped check strap is located below the lay and within which the picker stick oscillates, said device including a bracket fixed to the lay, a frame pivotally secured to said bracket for adjustment thereon, a pair of friction fingers fixed to said frame and engaging opposite faces of the check strap to cause the check strap to follow a sinuous path when moved by the picker stick, and means for locking said frame in adjusted position.

2. A friction device for a picker stick check mechanism of the type wherein a flexible looped check strap is located below the lay and within which the picker stick oscillates, said device including a bracket fixed to the lay, a supporting ledge on said bracket, an angularly adjustable frame pivotally secured to said ledge for adjustment thereon and having a pair of spaced friction fingers arranged to engage opposite faces of the check strap to retard movement of the picker stick when engaged thereby as the picker stick approaches the limit of its oscillating movement, and means for locking said frame in adjusted position.

3. A picker stick checking mechanism for a fly shuttle loom having a lay and a picker stick, said mechanism including a flexible looped check strap within which the picker stick oscillates, a bracket fixed to the lay and having a horizontal supporting ledge, an angularly adjustable frame on said bracket, a pair of spaced friction fingers on said frame arranged to engage opposite faces of said check strap, means for pivotally securing said frame in operating position on said bracket, and means for locking said frame in adjusted position.

4. A picker stick check mechanism for fly shuttle looms having a lay and a picker stick, said mechanism including a flexible looped check strap within which the picker stick oscillates, means attached to the lay for supporting the strap, a bracket attached to the lay and having a horizontal shelf projected away from said lay, a supporting frame adjustably secured to said horizontal shelf, said frame comprising a rearwardly extending portion pivotally secured to said shelf

and a pair of connected friction fingers arranged to engage opposite faces of said check strap and to retard movement of the picker stick as the latter approaches the limit of its oscillating movement, a pivotal connection between said frame and said shelf, and means for locking said frame in adjusted position.

5. A picker stick check mechanism for fly shuttle looms having a lay and a picker stick, said mechanism including a flexible looped check strap within which the picker stick oscillates, means attached to one side of the lay for supporting the check strap, a bracket attached to the other surface of the lay and having a projecting horizontal portion, a frame pivotally secured to said horizontal portion and having a pair of spaced substantially vertical friction fingers arranged to engage opposite faces of the check strap to retard the picker stick as it nears the limit of its oscillating movement, means for locking said frame in adjusted position, and means arranged to be gripped by the operator to move said frame into adjusted position and to hold said frame in adjusted position until said frame is locked in adjusted position.

6. A picker stick check mechanism for fly shuttle looms having a lay and a picker stick, said mechanism including a flexible looped check strap within which the picker stick oscillates, means attached to one side of the lay for supporting the check strap, a bracket attached to the other surface of the lay and having a projecting horizontal portion, a frame pivotally secured in position on the horizontal portion of said bracket, said frame including an upper portion having an opening therein, a depending portion fixed to said upper portion and forming a friction finger for engaging the outer face of said strap, a substantially horizontal position fixed to the lower end of said depending portion, and portion extending upwardly from said second horizontal portion and forming a second friction finger for engaging the other surface of said check strap, said fingers being disposed eccentrically relatively to the opening in said upper horizontal portion, and means for pivotally connecting said frame to said horizontal portion on said bracket and for locking said frame in adjusted position.

WALTER J. BUDZYNA.
